UNITED STATES PATENT OFFICE.

STEPHEN ARNOLD DOUGLAS MESSMORE, OF ASHVILLE, OHIO.

BUNDLING DEVICE.

Application filed January 18, 1927. Serial No. 161,799.

This invention relates to new and useful improvements in devices for facilitating the bundling of fodder, broom corn, rags, paper, etc., etc. and has for its primary object to provide a highly novel, simple, and inexpensive device for use in the compressing of a bundle of material so as to enable said bundle to be bound together by cord, wire or the like.

10 A further and important object is to provide such a device that may be readily transported from place to place and that may be operated by a single person, and this without requiring any unusual skill or a great amount 15 of labor.

The invention further aims to provide a bundling mechanism that includes generally a pair of pivotally interconnected curved arms between which the material to be 20 bundled is disposed, after which the arms are swung toward each other so as to make a tight bundle before tying the same.

With the foregoing and other objects in view as the nature of the invention will be 25 better understood, the same comprises the novel form, combination and arrangement of parts hereinafter more fully described, shown in the accompanying drawings and claimed.

30 In the drawings wherein like reference characters indicate corresponding parts throughout the several views:

Figure 1 is a view in side elevation partly in cross section of a bundling device constructed in accordance with the present invention, showing the bundle compressing arms in the act of being closed.

Figure 2 is a similar view disclosing the arms in open position.

40 Figure 3 is a vertical section taken substantially upon the line 3—3 of Figure 1.

Figure 4 is a fragmentary perspective of said arms together with the operating mechanism therefor, said arms being disclosed as 45 in fully closed position, and

Figure 5 is a perspective of a foot lever that is employed in conjunction with the present invention for the purpose of primarily moving one of the arms to partially 50 closed position.

Now having particular reference to the drawings, my novel bundling device consists of a suitable carrying frame that in the present instance consists of a pair of spaced 55 parallel bars 5—5 so shaped at their ends

as to provide carrying handles for the device, and depending from which bars are suitable supporting legs 6. These bars 5—5 are interconnected by transverse brace bars 7—7 while directly in back of one of the 60 brace bars 7 is a further cross bar 8.

Arranged transversely between the main bars 5—5 at a point slightly in front of the bar 7 remote from the last mentioned bar 8 is a pivot rod 9 upon which is pivotally 65 mounted the inner ends of a pair of curved arms 10 and 11, one of which is equipped at its inner end with an offset plate 12 that overlaps the end of the opposite arm so as to prevent the separation of the arms with 70 respect to each other.

The pivotal end of the innermost arm 10 is formed with a rearwardly extending tangential lever 13 to which is adjustably pivotally secured the inner inclined end 14 of a 75 foot lever 15 that is suspended adjacent its outer end between a pair of depending link bars 16—16 that are in turn pivotally secured at their upper ends to the adjacent brace bar 7 of the supporting frame previously described. The extreme outer end of this foot lever 15 is equipped with a foot plate 17 so as to facilitate the inward movement thereof.

Adjustably pivotally secured to the outer 85 end of the arm 11 is a rectangular shaped open lever 17 the outer end of which carries an operating handle 18. Pivoted to this lever 17 is a somewhat similarly shaped curved lever 19, the inner end of which is so 90 formed as to provide a hook 20 for engagement within any one of a plurality of spaced notches 21 formed at the outer edge of the innermost arm 10.

Obviously, when the arms 10 and 11 are 95 released and moved to open position as disclosed in Figure 2, they will rest respectively upon the front bar 7 and the cross bar 8. The material to be bundled may now be laid across the bars 5—5 of the supporting frame 100 between said arms after which pressure is applied to the foot lever 15 for swinging the innermost arm 10 into position over the top of the bundle. The hook 20 of the lever 19 is then engaged within a predetermined 105 one of the notches 21 in a manner as disclosed in Figure 1, after which the handle 18 of the lever 17 is pulled rearwardly for obviously tightly binding the bundle between said arms 10 and 11. After the lever 17 has 110

been thrown off of center, the arm 10 will be locked to the arm 11 to prevent the loosening of the bundle.

The arm 10 is equipped with a plate 22 at a point intermediate its ends, which plate is provided with an eye 23 through which cord, wire, or the like 24 may be placed, so as to facilitate the tying of the bundle after the same has been properly formed between the arms.

It will thus be seen that I have provided a highly novel, simple, and efficient bundling device that is well adapted for all the purposes designated and even though I have herein shown and described the invention as consisting of certain detail structural elements, it is nevertheless to be understood that some changes may be made therein without effecting the spirit and scope of the appended claims.

Having thus described the invention, what I claim is:—

1. In a bundling device of the class described, a supporting frame, a pair of coacting curved arms pivotally interconnected at their inner ends within said frame, and within which the material to be bundled is disposed transversely, means for initially closing one of the pivoted arms around the material, a frame-like lever pivoted at one end to the outer free end of the other arm and through which the free end of the first mentioned arm is adapted to extend, a handle at the other end of the frame-like lever, and an additional frame-like lever pivoted at one end to the intermediate portion of the first mentioned frame-like lever, and coacting means between said additional frame-like member and the free end of the first mentioned arm for causing the additional closing movement of said first mentioned arm in tight engagement with the material and for locking the arms around the same.

2. In a bundling device of the class described, a supporting frame, a pair of curved arms pivotally interconnected at their inner ends within said frame, and within which the material to be bundled is disposed transversely, a tangential extension formed on the pivoted end of the innermost arm, a foot lever operatively connected with said tangential extension for initially closing the inner arm around the material, a lever pivotally connected to the outer free end of the outermost curved arm, the innermost curved arm being provided with a series of spaced notches in its outer edge, and a pivoted locking dog carried by said lever for cooperation with any one of said notches for causing the

further movement of the innermost arm in tight engagement with the material and for locking the arms around the material.

3. In a bundling device of the class described, a supporting frame including parallel spaced longitudinal side bars, cross bars extending transversely between the side bars, supporting legs for the frame, a rod extending transversely between the side bars inwardly of the front cross bar, a pair of curved arms pivotally interconnected at their inner ends on said rod, said rod adapted to rest on the respective cross bars when in an open position, a tangential extension formed on the pivoted end of the innermost arm, a foot lever operatively connected with the tangential extension for initially moving the innermost arm around the material to be bundled, and additional means carried by the free end of the outermost curved arm for cooperation with the free end of the innermost curved arm for causing the further movement of the innermost arm in tight engagement with the material and for locking the arm around the material.

4. In a bundling device of the class described, a supporting frame including parallel spaced longitudinal side bars, cross bars extending transversely between the side bars, supporting legs for the frame, a rod extending transversely between the side bars inwardly of the front cross bar, a pair of curved arms pivotally interconnected at their inner ends on said rod, said arms adapted to rest on the respective cross bars when in an open position, a tangential extension formed on the pivoted end of the innermost arm, a foot lever operatively connected with the tangential extension for initially moving the innermost arm around the material to be bundled, and additional means carried by the free end of the outermost curved arm for cooperation with the free end of the innermost curved arm for causing the further movement of the innermost arm in tight engagement with the material and for locking the arm around the material, said last mentioned means comprising a lever pivoted to the outer end of the outermost curved arm, the free end portion of the innermost curved arm being provided with a series of spaced notches in the outer edge thereof, and a locking dog pivotally associated with the last mentioned lever and adapted for engagement with any one of said notches.

In testimony whereof I affix my signature.

STEPHEN A. D. ^{his} MESSMORE.
